UNITED STATES PATENT OFFICE.

ARTHUR H. LOVEJOY, OF GALLIA, NEW JERSEY.

AIR-HEATER.

SPECIFICATION forming part of Letters Patent No. 700,519, dated May 20, 1902.

Application filed December 17, 1901. Serial No. 86,208. (No model.)

To all whom it may concern:

Be it known that I, ARTHUR H. LOVEJOY, a citizen of the United States, and a resident of Gallia, in the county of Somerset and State of New Jersey, have invented a new and Improved Air-Heater, of which the following is a full, clear, and exact description.

The invention relates to heaters for heating buildings; and its object is to provide a new and improved air-heater arranged to utilize the fuel to the fullest advantage and to heat the air and conduct the same in a perfectly pure state into the rooms to be heated, the arrangement being such that each conduit extends from the air-inlet duct through the heater to an individual room without danger of the air being fouled with obnoxious gases, dust, and the like.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 is a sectional side elevation of the improvement on the line 1 1 of Fig. 2. Fig. 2 is a sectional plan view of the same on the line 2 2 of Fig. 1, and Fig. 3 is a reduced side elevation of one of the heater air-tubes.

In the foundation A for the heater is built or arranged a cold-air-supply chamber B, connected with a fresh-air-inlet conduit C, usually extending to the outside of the building, so that pure atmospheric air can pass into the chamber B. On the foundation A and over the chamber B is held a base-plate D, resting with its middle portion on a pillar B', arranged centrally in the chamber B. On this base-plate D is arranged an ash-pit E, over which is located a fire-box F, containing suitable grate-bars G for the ashes to pass from the fire-box into the ash-pit E and for supplying the necessary air to insure proper combustion to the fuel in the fire-box F. Air-tubes H extend through the base-plate D into the air-supply chamber B, the said tubes extending upwardly from the base-plate on the outside of the ash-pit E and fire-box F a suitable distance above the same to then bend in-

wardly and upwardly, as at H', until the opposite tubes meet each other, the tubes then extending straight upward, as at H'', to connect with tubes, pipes, channels h, or the like, each of which leads from a single pipe H to an individual room in the building. By having the tubes H provided with the inwardly and upwardly bent portions H' a combustion-chamber I is formed over the fire-box F, it being understood that the air in its passage from the chamber B through the tubes H is thoroughly heated by the heat emanating from the burning fuel in the fire-box F. A shell J, preferably of sheet metal, incloses the tubes H above the fire-box F, thus forming outside of the bent portions H' a heating-chamber, through which extends a smoke-flue K, leading from the combustion-chamber I to the chimney. In the front of the shell J is arranged a suitable fuel-supply door J' for passing the necessary fuel into the fire-box F, and a door (not shown) connects with the ash-pit E for removal of the ashes therefrom and for admitting more or less air to the ash-pit and to the grate-bars G.

As indicated in Figs. 1 and 2, the tubes H are set with their lower portion in a circle in the base-plate D; but this arrangement is not essential, as the tubes may be otherwise arranged, if desired.

From the foregoing it will be seen that when the heater is in use and the fuel is burning in the fire-box F, the heat emanating from the burning fuel intensely heats the tubes H, so that the air in the said tubes is heated and forced to rise to the individual rooms, a fresh supply of pure air always passing to the tubes from the supply-chamber B, connected by the conduit C with the outer air. By the arrangement described the air is conducted directly through the heater by the tubes H, so that there is absolutely no danger of obnoxious gases from the fire-box F and combustion-chamber I mingling with the air thus passing through the tubes H, and consequently heated pure air is furnished to the rooms to be heated. It is expressly understood that each room to be heated is connected with one of the tubes H, so that each room has its own direct supply of heated air from the chamber B.

Having thus described my invention, I

claim as new and desire to secure by Letters Patent—

1. An air-heater, having a series of air-tubes, each connected at one end with a cold-air-supply chamber, and at the other end with a distributing-pipe for conducting the heated air to a room, the said air-tubes being arranged side by side and extending around the fire-box, and ash-pit and forming a combustion-chamber above the fire-box, as set forth.

2. An air-heater, having a series of air-tubes, each connected at one end with a cold-air-supply chamber, and at the other end with a distributing-pipe for conducting the heated air to a room, the air-tubes having their lower portions extending along the outside of the fire-box and ash-pit, and the upper portions bent inwardly into contact with each other to form a drum or combustion-chamber above the fire-box and thence extended vertically, as set forth.

3. An air-heater, having a series of air-tubes, each connected at one end with a cold-air-supply chamber, and at the other end with a distributing-pipe for conducting the heated air to a room, the air-tubes having their lower portions extending along the outside of the fire-box and ash-pit, and the upper portions bent inwardly into contact with each other to form a drum or combustion-chamber above the fire-box and thence extended vertically, and a shell surrounding the air-tubes above the fire-box to form a heating-chamber between the shell and the outer sides of the upper bent portions of the air-tubes, as set forth.

4. An air-heater, having a series of air-tubes, each connected at one end with a cold-air-supply chamber, and at the other end with a distributing-pipe for conducting the heated air to a room, the air-tubes having their lower portions extending along the outside of the fire-box and ash-pit, and the upper portions bent inwardly into contact with each other to form a drum or combustion-chamber above

the fire-box, a shell surrounding the air-tubes above the fire-box to form a heating-chamber between the shell and the outer sides of the upper bent portions of the air-tubes and through the top of which the upper ends of the air-tubes extend, and a smoke-flue leading from the combustion-chamber and extending through the said heating-chamber, as set forth.

5. An air-heater, comprising a cold-air-supply chamber, a base-plate set over the said chamber, a fire-box and ash-pit on the said base-plate, and a series of air-tubes opening through the base-plate into the cold-air-supply chamber, the air-tubes extending upwardly along the outside of the ash-pit and fire-box, to then extend inwardly and upwardly into contact with each other to form a combustion-chamber over the fire-box and thence extended vertically, as set forth.

6. An air-heater, comprising a fire-box, an ash-pit below the fire-box, a series of air-tubes extending up along the outside of the ash-pit and fire-box and then bent inwardly into contact with each other above the fire-box to form a combustion-chamber above the same, the lower ends of the tubes being open for connection with a cold-air chamber and their upper ends adapted to be each connected with a distributing-pipe, a shell surrounding the upper portion of the said tubes and forming a heating-chamber around the same and through the top of which the upper ends of the air-tubes extend, and a smoke-flue leading from the combustion-chamber and extending into the heating-chamber to the front of the same and thence out through the rear thereof, as set forth.

In testimony whereof I have signed my name to this specification in the presence of two subscribing witnesses.

ARTHUR H. LOVEJOY.
